(57) **CLAIM**

The ornamental design for a pendant as shown and described.

DESCRIPTION

1.1 is a front perspective view of a pendant, showing our new design;

1.2 is a front view thereof;

1.3 is a back view thereof;

1.4 is a right-side view thereof;

1.5 is a left-side view thereof;

1.6 is a top view thereof; and

1.7 is a bottom view thereof.

The key features of the present design lie in the peculiar combination of the shape of the parts of the product, and the arrangement and shape of the gemstones comprised in the product.
